(57) **CLAIM**

The ornamental design for a dip net frame capable of flipping back and forth, as shown and described.

DESCRIPTION

FIG. 1 is a perspective view of a dip net frame capable of flipping back and forth showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view in use state;

FIG. 9 is a partial enlarged view of portion 9 shown in FIG. 1; and,

FIG. 10 is a partial enlarged view of portion 10 shown in FIG. 1.

The broken lines depict portions of the dip net frame capable of flipping back and forth and form no part of the claimed design.
